S. C. ROCKMAN,
COMBINATION GAS RANGE AND WATER HEATER.
APPLICATION FILED JUNE 23, 1915.

1,199,499.

Patented Sept. 26, 1916.

UNITED STATES PATENT OFFICE.

SOREN C. ROCKMAN, OF PHILADELPHIA, PENNSYLVANIA.

COMBINATION GAS-RANGE AND WATER-HEATER.

1,199,499.

Specification of Letters Patent. Patented Sept. 26, 1916.

Application filed June 23, 1915. Serial No. 35,912.

To all whom it may concern:

Be it known that I, SOREN C. ROCKMAN, a citizen of the United States, residing at Philadelphia, in the county of Philadelphia 5 and State of Pennsylvania, have invented certain new and useful Improvements in Combination Gas-Ranges and Water-Heaters, of which the following is a specification.

My invention relates to "gas ranges."

10 The object of my invention is to construct such ranges with water heating means for a continuous supply of hot water and also means for storing a quantity of water for bathing and washing, besides a receptacle 15 for supplying small quantities of hot water used for kitchen purposes.

In the drawing Figure 1 is a front view and Fig. 2 is an end view of Fig. 1. Fig. 3 is a plan view and Fig. 4 is a cross section of 20 cooking top 2.

Similar letters refer to similar parts.

In the drawing, 1 is the body of the gas range, having a gas cooking top 2 and oven 3 and a broiler oven 4.

25 5 is a double burner, inclosed in a casing 6 and receiving air from below through openings in plate 7 having bent up angles, whereby the plate is strengthened and stiffened and secured to the legs of the range.

30 Over the gas burner and within the casing 6 is a coil 10, having a cold water inlet 11, through which the water passes the coil 10 and out from the top thereof, is led to the bottom of a coil 12, to which it is connected

35 and through which the water passes, to a preliminary tank 13 of the sides, sufficient for small quantities of water used for kitchen purposes, thereby saving the heating of the water in the larger storage

40 tank 14, used for washing and bathing. A valved pipe leads from said small tank 13 to a storage boiler 14. The boiler 14 has a pipe 11', leading to coil 12, so as to form a circulation of the water in the boiler

45 and in the coil, for reheating the water and again passed into the tank 14. The boiler is secured in the cross girt and further fully secured to a vertical plate 16, connecting plate 17 to the legs of body 1. The gas for

50 the burner under the coils 10 and 12 is received through pipes 17', which is secured to a casing 18 and is adapted to a needle valve 19, secured intact to a diaphragm 20 on casing 18. A diaphragm 18' is secured to

55 casing 6 and connected by a pipe 21, to the coil 10, so that when the pressure of water

in the coil or coils 10 and 12, or in the boiler 14 is above a pre-determined point, at which the temperature of the water is desired to be, the diaphragm 18' will automatically 60 operate the needle valve 19, to cut down the supply of gas to the burners 5. The outer face of the diaphragm 18' is engaged by the lower end of a small lever which is fulcrumed on a projection on the casing 6. The 65 upper end of this small lever has an adjusting screw which bears against the casing 6 and is adapted to hold the lower end of the lever in an adjusted position in which it will prevent the operation of the diaphragm 18' 70 to such an extent as to entirely cut off the supply of gas to the burners, so that a flame will always be present for the ignition of the gas when its supply is automatically increased by the operation of the diaphragm 75 18' on the needle valve 19.

The outside part of the needle valve is provided with a stud 22 and may have a jaw nut, whereby the said needle valve may be adjusted, to be acted on by the diaphragm, 80 actuated by the pressure of the steam on it, when the temperature and pressure is at the desired point.

At the end of the shelf 7 and below the boiler 14, I may place and secure to said 85 plate 7, a radiator 7' that may be connected up at its bottom through valved pipes, in the usual well known way, to a source of supply of hot water (such as the heater in the cellar or a source that may heat the 90 kitchen) said radiator 7' on said plate 7, at its bottom, a pipe coil secured to the bottom side of the plate 7, which may lead to radiators, in the several rooms of the house or apartment. A wire screen basket may be 95 secured below plate 7 right under the burner, through which the air passes to the burner.

Having thus described my invention, I claim:

1. The combination of a supporting frame, 100 a water heating coil, a gas burner beneath said coil, means to supply gas to said burner, said means including an adjustable valve governing the supply of gas to the burner, a diaphragm operated by the pressure within said coil and operatively connected to said valve, and adjustable means limiting the movement of said diaphragm and preventing the closing of said valve.

2. The combination of a supporting frame, 110 a water heating coil, a gas burner beneath said coil, means to supply gas to said burner,

- said means including an adjustable valve governing the supply of gas to said burner, a diaphragm operated by the pressure within said coil and operatively connected to said valve, an adjustable lever adapted to engage and limit the diaphragm and prevent the closing of said valve, and an adjustable set screw adapted to hold said lever in different positions of adjustment.
- 10 3. The combination of a supporting frame, a casing, a water heating coil within said casing and having a water inlet opening in the lower end thereof, a pipe communicating with and extending downwardly from the upper end of the coil, a second coil within said casing laterally adjacent to the first named coil and having its lower end communicating with the lower end of said pipe, a water tank communicating with the lower end of the first named coil and with the upper end of the second named coil, and gas burners beneath said coils.
- 15 4. The combination of a supporting frame, a casing, a water heating coil within said

casing and having a water inlet opening in 25 the lower end thereof, a pipe communicating with and extending from the upper end of the coil, a second coil within said casing laterally adjacent to the first named coil and having its lower end communicating 30 with the lower end of said pipe, a preliminary tank above and communicating with the upper end of the second named coil, a relatively larger storage tank below said preliminary tank, a pipe affording communication 35 between said preliminary tank and the upper portion of said storage tank, a pipe affording communication between the lower portion of said storage tank and the lower end of the first named coil, and gas burners 40 beneath said coils.

In testimony whereof I affix my signature in presence of two witnesses.

SOREN C. ROCKMAN.
